UNITED STATES PATENT OFFICE.

EDWIN T. FARMER, OF CARTHAGE, MISSOURI.

SPOOL-CASE.

1,333,479.

Specification of Letters Patent.

Patented Mar. 9, 1920.

Application filed February 2, 1918, Serial No. 215,109. Renewed September 8, 1919. Serial No. 322,503.

To all whom it may concern:

Be it known that I, EDWIN T. FARMER, a citizen of the United States, residing at Carthage, in the county of Jasper and State of Missouri, have invented new and useful Improvements in Spool-Cases, of which the following is a specification.

This invention relates to cases adapted to hold spool cotton and the like and it consists in the novel features hereinafter described and claimed.

An object of the invention is to provide a case of simple structure in which the spools may be placed and held in a manner that they may be visible from the front of the case, there being also provided in conjunction with the case means for dispensing or delivering the spools successively as it is desired to remove them from the case. Also the invention contemplates the provision of means which will have a tendency to prevent the spools from being introduced into the case endwise and thus assuring that the spools as they arrive at the delivering means will be in proper position for reception by the said means.

With this object in view the case comprises a body having at its front side a transparency and provided with side walls which extend below the said transparency.

The side walls are mounted upon a suitable base whereby the case is supported. A cover is hingedly mounted at the upper end of the case and a spring is located in the upper portion of the case and serves to prevent the spools from being introduced in the case endwise. A block is pivotally mounted between the lower portions of the side panels of the case and below the transparency and is provided at its upper portion with a notch adapted to receive a single spool. The said block is so weighted or pivoted that a solid portion thereof normally lies below the column of spools and when it is desired to remove a single spool the forward end of the block is swung in an upward direction whereby the notch is brought below the column of spools and one of the spools enters the same. The block is then released whereby its forward portion descends and the spool which is in the notch is brought toward the front of the case and may be removed from the notch while the spools which remain in the case are supported upon the rear solid portion of the block.

In the accompanying drawing:—
Figure 1 is a front elevation of the spool case.

Fig. 2 is a vertical sectional view of the same.

The spool case comprises a body 1 which is composed of side panels 2, a back panel 3 and a front transparent panel 4. All of the said panels have their upper edges substantially flush or at the same level but the lower portions of the side panels 2 extend below the lower edges of the back panel 3 and the transparency 4. The side panels 2 are provided at their inner edges with grooves 5 which receive the edge portions of the transparency 4 and ledges or clips 6 are secured at their ends to the side panels 2 and receive and support the upper and lower edge portions of the transparency 4. The side panels 2 are mounted at their lower ends upon a suitable base 7. A spring member 8 is attached at one end to the upper portion of the back panel 3 and extends into the body 1. The spring 8 is flat and serves as means which will tend to prevent the spools from being introduced into the case in edgewise position, in other words the spools should be placed in the case in horizontal position. A cover 9 is hingedly connected with the side panels 2 at the rear portion thereof and the said cover is bounded around three edges by a depending flange 10 which is adapted to fit snugly against the outer surfaces of the side panels 2 and the upper clip 6 when the cover is in a closed position over the body 1. The cover 9 is provided at its free edge portion with a handle 11.

A block 12 is pivotally mounted between the lower portions of the side panels 2 and at the rear edges thereof and the said block lies below the lower edges of the back panel 3 and the transparency 4. The block 4 is provided at its upper intermediate portion with a notch 13 which is adapted to receive a single spool. The block 12 is provided at its forward ends with a handle 14. The block 12 is so connected with the side panels 2 that its center of gravity lies in front of the point of pivotal connection between the block and the said side panels. Consequently the said block normally lies in an inclined position and its rear solid portion normally lies under the column of spools which is retained in the body 1.

When it is desired to remove a spool from

the body the forward end of the body 12 is raised by using the handle 14 whereby the notch 13 is carried under the column of spools and the spools descend whereby the 5 lowermost spool enters the said notch.

The block 12 is then released whereby its forward end descends in response to gravity and the spool which is in the notch 13 is carried forward and beyond the front side 10 of the body 1. However, portions of the rear part of the ends of the spools will remain behind the forward edges of the side panels 2 and consequently the spool is retained against falling out of the notch 13 15 when it is brought to a forward position. However, the spool may be readily lifted out of the notch and thus the said spool is removed from the body of the case while the other spools are retained therein and 20 while they may be readily observed through the transparency they are protected against the accumulation of dust, dirt and the like. The block 12 may be provided upon the upper portion of its forward end with a 25 legend 15 which will indicate the size, weight or character of the cotton which is carried by the spool.

If an attempt is made to insert a spool endwise in the body 1 the spool will wedge 30 between the spring 8 and the front or sides

of the body. Therefore the spool must be turned to a horizontal position when it will readily roll by the spring as it is flexed and the spool will drop in the bottom of the body in proper position.

From the foregoing description taken in conjunction with the accompanying drawing it will be seen that a spool case of simple and durable structure is provided and that the same may be used to advantage 40 for retaining a column of spools in a manner that they may be withdrawn or dispensed successively as desired or required.

Having described the invention what is 45 claimed is:—

A spool case comprising a body having an opening at its upper end for the entrance of the spools and an opening at its lower end for the exit thereof, a dispensing means located below the exit opening of the body, 50 a closure for the entrance opening of the body, and a spring member fixed to the side of the body and having a free end portion extending into the body immediately below said entrance opening and serving 55 to prevent the introduction of spools in an endwise position.

In testimony whereof I affix my signature.

EDWIN T. FARMER.
